FRANK KUHN AND LAURENCE H. THOMAS, OF DETROIT, MICHIGAN, ASSIGNORS TO AMERICAN ELECTRICAL HEATER COMPANY, OF DETROIT, MICHIGAN, A CORPORATION OF MICHIGAN

SUBASSEMBLY FOR ELECTRICAL HEATERS

Application filed March 18, 1929. Serial No. 348,063.

This invention relates to electric heaters and more particularly to thermostatically controlled electric irons.

One of the primary objects of this invention is to facilitate the assembly of heaters of the foregoing type by reducing the number of separable parts thereof to a minimum.

The invention contemplates accomplishing the foregoing result by providing a sub-
10 assembly for heaters wherein the heating element, thermostat and terminal supporting brackets form a unitary construction and as a consequence may be readily assembled with or detached from the heater as a unit.

15 Other objects and novel features of the invention will be made more apparent as this description proceeds; especially when considered with the accompanying drawing, wherein

20 Figure 1 is a fragmentary side elevational view of a thermostatically controlled iron embodying our invention, and having certain parts thereof broken away for the sake of clearness,

25 Figure 2 is a plan view of the sub-assembly,

Figure 3 is a sectional view taken on the line 3—3 of Figure 2,

30 Figure 4 is a sectional view taken on the line 4—4 of Figure 2, and

Figure 5 is an end elevation of the construction shown in Figure 2.

Referring now to the drawing, it will be noted that there is illustrated therein an electric iron 10 having a heat distributing base plate 11, a heating element 12 seated upon the base 11, a pressure plate 13 and a hood 14, provided with the conventional handle. (Not shown.) For holding the base plate

40 10, heating element 12 and pressure plate 13 in assembled position, we provide a series of bolts 16 having the head portions thereof bearing upon the top surface of the pressure plate and the shank portions thereof extending

45 through apertures formed in the pressure plate and threaded into the base plate 11. The hood 14 is preferably held in proper assembled position by a single stud element 17 threaded into the pressure plate 13 and

50 projecting upwardly therefrom through an

opening 18 in the top of the hood for receiving the clamping nut 19.

As shown particularly in Figure 2 of the drawing the heating unit is completely enclosed by a metallic covering 20 and is provided with an elongated slot 21 extending from the rear edge of the heating element to a point adjacent the center thereof. Secured to the rear end of the heating element adjacent the slot is a bracket assembly 22. This assembly comprises a supporting member 23 having an upwardly extending portion 24 electrically connected to the heating element by means of a conductor 25 extending from the heating element and secured to the upwardly extending portion 24 by means of a fastening element 26. The upwardly extending portion 24 of the supporting member 23 terminates in a laterally projecting flange 27 forming a support for the base 28 of a terminal contact carrying lug 29. As shown in Figure 4 of the drawing the base 28 is insulated from metallic contact with the flange 27 by means of a suitable insulating strip 30 and is secured to the flange 27 by a suitable fastening element 31 which is also insulated from metallic contact with the flange 27 by means of the mica washer 32. The upper portion of the lug 29 is preferably provided with side flanges 33 embracing opposite sides 70 of the terminal contact 34 so as to prevent the same from movement relative to the lug 29. The terminal contact 34 is detachably secured to the lug by means of a screw 35.

The cooperating terminal contact element 36 is detachably secured to a lug 37 having a base portion 38 secured to the heating element 12 adjacent the bracket assembly 22 upon the opposite side of the slot 21. The contact element 36 is electrically connected 80 to the heating element 12 by means of a suitable conductor 39 extending from the heating element and secured to the lug 37.

For controlling the temperature of the iron a suitable thermostatic switch 40 is provided having a casing 41 and bi-metallic thermostatic strips 42 secured at one end to the casing. As shown the switch is arranged directly beneath the slot 21 in the heating element and is provided at the rear end with 95 100

terminal contact elements 43 and 43', electrically connected to the strips 42 and adapted to extend through the slot 21 adjacent the bracket assembly 22. Threadedly mounted 5 upon the forward end of the thermostat casting adjacent the free ends of the thermostatic strips is a suitable adjusting element 44. The latter preferably extends upwardly from the thermostat through the slot 21 and 10 through aligned openings in the pressure plate 13 and hood 14 to a control element 45 outside of the hood. The lower portion of the adjusting element is arranged in the path of travel of the lowermost thermostatic strip 15 so as to intercept the same at a predetermined point to effect a separation of this strip from the upper strip under changing temperature conditions.

For securing the thermostatic switch in the 20 assembly and at the same time electrically connecting the thermostat in the circuit the conductors 46 and 47 are provided. The conductor 46 is secured to the supporting member and electrically connected to the heating 25 element by the fastening element 26 and is detachably secured to the thermostatic switch terminal 43 by means of a screw 48. The conductor 47 on the other hand is preferably secured to the lug 29 and electrically 30 connected to the terminal contact 34 by means of the fastening element 31 which also functions to secure the bracket in assembled position. The free end of the conductor 47 is detachably secured to the thermostatic terminal 43' by means of a screw 49. Thus it 35 will be apparent that the thermostatic switch may be readily detached from the heating element and iron as a unit by merely removing the screws 48 and 49. It will also be 40 noted that by reason of the fact that the conductors 46 and 47 are the only means utilized for connecting the thermostat to the heating unit or to the iron, the forward end of the thermostat will be capable of slight angular 45 movements relative to the remaining parts of the iron. This is important as it permits the adjusting element to align itself readily with the control member 45 during assembly of the iron and prevents binding of the element during 50 adjustment of the same.

Thus from the foregoing it will be noted that we have provided a compact and durable iron assembly wherein the heating unit, 55 terminal contact elements and thermostatic switch form a sub-assembly that may be readily detached from or assembled with the iron as a unit. It will further be noted that we have provided a bracket assembly, which in addition to supporting and electrically connecting the thermostatic switch to the heating element, operates to support one of the 60 terminal contact elements.

What we claim as our invention is:

1. A sub-assembly for electrical heaters including, a heating element having an elongated slot therein, a thermostatic switch arranged beneath the slot and having contact elements extending therethrough, and a bracket secured to said heating element adjacent to said slot and electrically connected to said contact elements whereby the thermostat, heating element and bracket form a unitary construction. 70

2. A sub-assembly for electrical heaters including, a heating element having an elongated slot therein, a thermostatic switch arranged beneath the slot and having contact elements extending therethrough, a bracket secured to said heating element adjacent to said slot, and means for connecting the thermostatic switch to the heating element including electrical conductors secured to the bracket and detachably secured to the contact elements aforesaid. 75

3. A sub-assembly for electrical heaters including, a heating element having an elongated slot therein, a thermostatic switch arranged beneath the slot and having contact elements extending therethrough, a bracket assembly secured to said heating element adjacent to said slot, said bracket assembly comprising a plurality of superimposed parts insulated from each other, one of said parts adapted to support a terminal contact element and another of said parts having an electrical connection with the heating element, and means for connecting the thermostatic switch to the heating element including electrical conductors extending from the thermostatic switch contact elements, and secured to the bracket, one of said conductors being connected to the terminal contact element and the other of said conductors being connected to the electrical connection between the bracket and heating element. 85 90 95 100 105

4. A sub-assembly for electrical heaters including, a heating element, a thermostatic switch arranged to one side of the heating element and having contact elements extending through the heating element, and a bracket carried by said heating element and electrically connected to said contact elements whereby the thermostat, heating element and bracket form a unitary construction. 110 115

5. A sub-assembly for electrical heaters including, a heating element, a thermostatic switch arranged to one side of the heating element and having contact elements extending through the heating element, and a bracket carried by the heating element formed of complementary parts insulated from each other, means connecting one of the contact elements aforesaid with one of said parts, and means connecting the other of said contact elements with the other of said parts. 120 125

6. A sub-assembly for electrical heaters including, a heating element, a thermostatic switch, a bracket rigidly secured to the heating element and formed of complementary parts insulated from each other, means con- 130

necting one of said parts to the thermostat for supporting the latter and a terminal contact member secured to the other part of said bracket.

- 5 7. A sub-assembly for electrical heaters including, a heating element, a thermostat, a bracket carried by the heating element formed of complementary parts, means for securing said parts together and a member
10 carried by said thermostat and secured to said bracket by the securing means aforesaid whereby said bracket, heating element and thermostat form a unitary construction.

8. A sub-assembly for electrical heaters in-

cluding, a heating element, a thermostat for controlling the operation of the heating element, a bracket carried by the heating element formed of complementary parts, means for securing said parts together and insulating the same from each other, contact members carried by said thermostat and secured respectively to said parts, and a terminal contact member secured to one of said parts.

In testimony whereof we affix our signatures.

FRANK KUHN.
